UNITED STATES PATENT OFFICE.

LOUIS MYERS, OF NEWARK, NEW JERSEY, ASSIGNOR, BY MESNE ASSIGNMENTS, TO
THE FIRM OF NEWELL & NEAL.

SAFETY-CHEST.

1,044,228.

Specification of Letters Patent. Patented Nov. 12, 1912.

Application filed December 11, 1907. Serial No. 406,037.

To all whom it may concern:

Be it known that I, LOUIS MYERS, a citizen of the United States, residing in Newark, county of Essex, and State of New Jersey, have invented certain new and useful Improvements in Safety-Chests, of which the following is a specification.

My present invention relates to improvements in safety chests or receptacles adapted to contain jewelry or other valuables, and provided with an automatically operated burglar alarm designed to prevent the theft of the chest or the removal of its contents.

In general design the chest proper of my present invention is of substantially the same construction as covered by my pending application filed March 22nd, 1907, Serial No. 363,883.

The improvements in my present case relate to the locking mechanism for the chest, and to an electric alarm mechanism automatically controlled by an unstable ball or weight, and having means actuated by the locking mechanism for setting and disconnecting the alarm mechanism so that the alarm will be placed in condition for operation when the chest is locked, and will be thrown into inoperative position when the chest is unlocked.

In order that my invention may be fully understood, I will first describe the same with reference to the accompanying drawings, and afterward point out the novelty more particularly in the annexed claims.

In said drawings Figure 1 is a front elevation of my improved safety chest showing the cover raised into open position, a part of the chest being broken away to expose the electric battery. Fig. 2 is an end elevation of the same, the raised cover being shown in vertical section. Fig. 3 is a vertical sectional view of the automatic controlling device for the alarm mechanism. Fig. 4 is a detail inside plan view of the same. Fig. 5 is an inside elevation of the cover with the alarm mechanism and controlling device removed, this view being similar to the view of the cover shown in Fig. 1, with the locking mechanism in shifted and locked position. Fig. 6 is a detail side elevation of two of the locking bolts and their operating mechanism. Fig. 7 is a detail plan view of a part of the main body of the chest illustrating the spirit levels for leveling the chest

upon its support, and also showing one of 5 the bolt receiving sockets or openings.

The chest proper is preferably formed of inner and outer spaced shells 1 and 2 as fully set forth in my above named application Serial No. 363,883. Since it is necessary to the proper operation of my improved automatically controlled alarm mechanism that the chest be placed upon a perfectly level surface, I provide the spirit levels 5 and 10 in the upper edge of the walls of the 65 main body of the box as shown in Fig. 7.

15 is the top of the box or chest which is preferably formed of inner and outer walls or shells as described in my above named application. This top may be hinged to 70 the main body of the chest or it may be entirely removable therefrom. I have not shown the details of the mounting of the cover upon the box, but the cover is preferably hinged at one of its long edges to the 75 upper edge of the box proper.

I prefer to mount the locking mechanism and the alarm mechanism entirely upon the cover, placing these mechanisms upon the inside of the cover so that they are entirely 80 inclosed and protected when the chest is closed and locked.

It will be observed particularly with reference to Fig. 7 that the upper edge of the main body portion of the chest is formed 85 with bolt receiving slots or keepers 20, it being preferable to provide four of such keepers 20, one near each corner of the box to receive the locking hooks 25 formed integral with the longitudinal movable locking 90 bolts 26. There are four of these locking bolts 26, each one of which is provided with two longitudinal slots 27 in which engage the guiding and retaining pins 28 rigidly mounted in the flanged portion of the cover 95 15. These locking bolts 26 are arranged between the inner and outer walls of the cover of the chest, the guiding pins 28 being mounted in said walls. The locking hooks of the bolts 26 project through slots 29 in 100 the facing flanges 30 of the cover.

35 and 36 are bolt operating levers pivotally mounted at 37 upon the inner face of the cover 15. The opposite ends of each of these operating levers 35 and 36 are 105 slotted or forked as indicated in dotted lines in Fig. 5 to engage the pins 38 upon the locking bolts 26, so that when the levers 35

and 36 are moved upon their pivot 37, all of the locking bolts 26 will be correspondingly moved inwardly or outwardly into unlocked or locked position.

5 For controlling and actuating the operating levers 35 and 36, I have arranged a rocking arm or lever 40, centrally journaled upon the inner face of the chest cover at 41, and carrying in its opposite ends the 10 laterally projecting pins or lugs 42, which engage and operate in the cam slots 43 formed in the operating levers 35 and 36, and extending at an angle to the longitudinal axis of said levers. When the lever 15 40 is rocked, pins 42 will cause the levers 35 and 36 to be correspondingly moved for operating the bolts.

20 50 is a permutation lock suitably mounted in the cover 15 adjacent to the front edge 25 and having the operating knob or handle 51 projecting outwardly in convenient position to be operated. This permutation lock 50 is of ordinary construction, and is not illustrated in detail in the accompanying drawings, except to show a plurality of tumbler disks 52, each one of which is formed with a notch or gate 53 in the usual manner.

30 55 is a dog or detent pivoted at 56 and 35 having a rectangularly projecting nose 55^a which is adapted to engage and enter the gates 53 of all the tumblers, when the combination of the lock has been properly set. A leaf spring 57 mounted upon the rocking

35 lever 40 engages the dog or detent 55 and moves it into engagement with the gates of the tumblers when the tumblers have been set. By this means the dog or detent 55 is engaged by the rotatable permutation lock 40 so that the lever 40 can be rocked upon its pivot 41 for actuating the levers 35 and 36 to thereby move the locking bolts into and out of locking position.

45 60 and 61 are the bells and 62 is the hammer 45 of an ordinary electric bell. The hammer 62 is mounted upon the spring actuated armature lever 63 which is mounted in operative relation to the electro-magnets 64.

50 65 is a battery mounted in a compartment 50 in one end of the body portion of the chest, and 66 and 67 are the battery terminals. A wire indicated at 69 is run from the battery terminal 66 to the bell terminal 68. Another wire indicated at 70 is run from the battery 55 terminal 67 to the end of a contact lever 71 hereinafter referred to, and a third wire indicated at 72 is run from a contact plate 73 to the other bell terminal 74, it being understood that one of the bell terminals 68 or 74 60 is connected with the frame of the bell, while the other is insulated therefrom, and electrically connected to one of the terminal wires of the electro-magnets. From this explanation it will be understood that when the 65 contact lever 71 is in engagement with the

contact 73, the bells 60 and 61 will be sounded.

80 is a hollow cylindrical box secured to the inner face of the cover 15 of the safety chest. This box 80 is preferably formed of some insulating material such as rubber, fiber or porcelain. This box 80 is secured to the face of the chest cover by long screws passing through it into the cover as shown at 81 and 82. A circular opening 85 is formed in the inner wall of the box or cover to receive a small conoidal block 86, which is mounted upon and projects upwardly from the contact lever 71. This contact lever 71 is freely journaled upon a screw 87, and is 80 engaged by leaf spring 88 secured to the box 80 at 89, so as to tend to move the contact end of lever 71 into engagement with contact 73, and at the same time elevate the conoidal block 86 in the opening 85 of 85 box 80.

90 90 is a spherical weight freely mounted in the cylindrical cavity 80^a of box 80 so as to be capable of rolling around therein under the influence of the displacement of the chest. 90 When the box is supported in perfectly level position and the contact lever 71 is held in position to break the electric circuit and hold the conoidal block 86 downwardly in the opening 85, the spherical weight 90 will 95 naturally rest in the opening 85, said opening affording a slight depression or seat for retaining the spherical weight in that position.

95 95 is a throw-out lever pivoted upon the inner end of the box 80 at 96 and having one end projecting through a slot 97 formed in one of the locking bolts 26 so that the lever will be rocked upon its pivot every time the bolt is shifted longitudinally. The 100 opposite end of the throw-out lever 95 is formed with a laterally projecting curved blade which is presented in the channel 80^b cut transversely across the end of the box 80 in position to engage the free end 71^a of 110 the contact lever 71 to move the contact lever into inoperative position. This throw-out lever 95 is operated for breaking the circuit controlling the electric bell when the bolts 26 are unlocked.

115 120 The operation of the device will be clear from the following brief description: The safety chest is placed upon a table or other support and arranged as nearly as practicable in level position. The valuables being placed in the chest, the cover is closed. When the cover is closed, and before the bolts are locked, it will be observed that the throw-out lever 95 is in position to engage the contact lever 71 so that the circuit for the electric bell is broken. This position of the throw-out lever 95 also holds the conoidal block 86 withdrawn partly from the opening 85 in the hollow block 80, so that the ball or weight 90 will have come to a

position of rest in engagement with the opening 85 as shown in full lines in Fig. 3 of the drawings. The lock mechanism is then operated for locking the chest and the combination disturbed so that it cannot be unlocked without a knowledge of the combination. As the bolts are locked it will be observed that the throw-out lever 95 is withdrawn out of engagement with the contact lever 71 so that the spring 88 will tend to move lever 71 into position to complete the circuit which rings the bell. When, however, the lever 95 is withdrawn, the ball or weight 90 is in a position of rest above the opening 85 so that when the spring actuated contact lever 71 is released, it will move the conoidal block 86 genuly up into engagement with the ball or weight 90, the weight of which is sufficient to withstand the pressure of the spring 88. In this position the ball or weight 90 holds the contact lever out of contact with the plate 73 so that the chest may remain in this set position until disturbed. If the box should be shaken or moved from its horizontal position, the ball or weight 90 will immediately roll away from its position of rest above the conoidal block 86, which will permit the spring 88 to force the lever 71 into contact position, which will cause the electric bell to ring. The moment this action has taken place, the conoidal block 86 will have assumed a position projecting up through the opening 85 into the box 80, so that the ball or weight 90 cannot by any possible means be replaced in position to break the circuit and stop the alarm. The bell will, therefore, continue to ring, and will attract attention to the unauthorized disturbance of the chest, until the chest is unlocked by the person having knowledge of the combination. When the chest is unlocked, the electric circuit is broken as above explained, and the alarm arrested.

It will be observed from Fig. 2 of the drawings that the sound from the electrical alarm has free outlet through the openings 100 in the inner wall of the cover 15 and through opening 101 in the outer wall of the cover into the perforated raised crown piece 102 secured to the top of the cover.

What I claim is:

1. A safety chest having a locking mechanism, in combination with an electric alarm, two contact members, one of which is movable, included in the circuit of the alarm, an unstable weight normally engaging the movable contact member and holding it out of contact with the other member, and means actuated by the unlocking of said chest for positively locking the movable contact member out of contact.

2. The combination of a safety chest having a top or cover, suitable locking mechanism therefor, an electric alarm mounted

within the chest, automatically operating contact members included in the circuit of the electric alarm, means controlled by the locking mechanism for positively breaking the circuit through said contact members, and an unstable weight adapted to engage one of said contact members and retain it in circuit broken position until the weight is disturbed. 70

3. A safety chest having a locking mechanism, in combination with an electric alarm, an automatically actuated circuit closing member included in the circuit with said alarm, a ball weight adapted to engage said circuit closing member and hold it in circuit broken position, means for supporting said ball weight in operative relation to said circuit closing member, and means actuated by the unlocking of said chest adapted to engage the circuit closing member and move it into circuit broken position, to permit the ball weight to move into operative engagement therewith. 75

4. A safety chest having a locking mechanism, in combination with an electric alarm, a circuit closing member included in the circuit with said alarm, a ball weight, a supporting wall for said ball weight having an opening through it, a part projecting from said circuit closing member into the opening of said supporting wall in position to be engaged by said ball weight, and means operated by the unlocking of said chest for moving said circuit closing member into circuit broken position to permit the engagement of the ball weight with the part projecting from the circuit closing member into said wall opening. 90

5. The combination of a chest or receptacle, an alarm within said chest or receptacle, a circuit and relatively movable contacts controlling said electric alarm, suitable locking mechanism for said chest or receptacle, means actuated by the locking mechanism for separating said electric contacts and breaking said circuit, and a ball or weight supported above the movable contact member to normally hold it in circuit broken position and adapted to be actuated by the displacement of the chest or receptacle for automatically releasing said contact member to sound the alarm. 105

6. A safety chest having a locking mechanism, in combination with an electric alarm, a battery in circuit with said alarm, a stationary contact member included in said circuit, a pivotally mounted spring actuated contact lever supported in operative relation to said stationary contact member and also included in said circuit, a part projecting from said contact lever, a support formed with an opening into which said part is adapted to project, and a ball or weight freely mounted upon said support and adapted to engage said part for holding 110

the contact lever out of contact with the stationary contact member, said electrical circuit being likewise under the positive control of said locking mechanism.

5 7. The combination of a chest or receptacle, an electric alarm within said chest or receptacle, a pivotally mounted contact controlling said electric alarm, suitable locking mechanism for said chest or receptacle, 10 means actuated by the locking mechanism for separating said contacts and breaking said circuit, and a ball or weight supported above the pivoted contact to normally hold it in circuit broken position and adapted to 15 be actuated by the displacement of the chest or receptacle for automatically releasing said contact member to sound the alarm.

8. The combination of a chest or receptacle, an electric alarm within said chest or receptacle, a pivotally mounted contact controlling said electric alarm, a ball or weight supported above the pivoted contact to normally hold it in circuit broken position and adapted to be actuated by the displacement of the chest or receptacle for automatically releasing said contact member to sound the alarm, suitable locking mechanism for said chest or receptacle, and a pivoted lever actuated by the locking mechanism for separating said contacts and breaking said circuit.

9. A safety chest having a locking mechanism, in combination with an electric alarm, a battery in circuit with said alarm, a stationary contact member included in said circuit, a pivotally mounted spring actuated contact lever supported in operative relation to said stationary contact member and also included in said circuit, a projection upon said contact lever, a hollow box formed with an opening in which said projection operates, and a ball or weight freely supported in said hollow box adapted to engage said projection for holding the contact lever out of contact with the stationary contact member, said electrical circuit being under the positive control of said locking member.

10. In a safety chest, the combination of 50 an electric alarm, a battery in circuit with said alarm, a stationary contact member included in said circuit, a pivotally mounted spring actuated contact lever supported in operative relation to said stationary contact member and also included in said circuit, a projection upon said contact lever, a hollow box formed with an opening in which said projection operates, a ball or weight freely supported in said hollow box 55 adapted to engage said projection for holding the contact lever out of contact with the stationary contact member, a controlling

lever formed with a laterally projecting blade which is adapted to engage the end of the contact lever for moving it into circuit 65 broken position, and means for operating said controlling lever.

11. In a safety chest, the combination of an electric alarm, a battery in circuit with said alarm, a hollow box of insulating material formed with an opening through its bottom wall, a spring actuated contact lever pivotally mounted upon said box and included in the circuit with said alarm and battery, a projection on said contact lever 70 operating in said box-wall opening, a ball or weight freely supported in said hollow box adapted to engage said projection for holding the contact lever in circuit broken position, a controlling lever pivotally 75 mounted upon said box in position to engage the end of the contact lever for moving it into circuit broken position, locking mechanism for the chest, means operatively connecting the controlling lever and locking 80 mechanism, and means for operating said locking mechanism and controlling lever to break said electrical circuit and prevent said alarm from operating.

12. In a safety chest or receptacle, the combination of the main body of the chest, a top or cover therefor, suitable locking mechanism for securing the top or cover upon the main body, an electric alarm mechanism, a hollow cylindrical box supported upon 90 the top or cover and formed with an opening through its bottom wall, a contact lever pivotally mounted upon said hollow box and formed with a block or projection which operates in the opening in the bottom of the 95 box, a stationary contact member with which the contact lever cooperates, a circuit including the electric alarm and said contact members, a ball or weight freely mounted in said hollow cylindrical box, and a throw-out 100 lever pivoted upon said box and engaged by the locking mechanism and formed with a laterally projecting blade, which is adapted 105 to engage the contact lever.

13. The combination with a safety chest 110 having a locking device, of an electrically operated alarm, a circuit therefor, unstable means for controlling said circuit comprising a gravity-operated device, said means adapted, when said receptacle is tipped, to 115 permit said circuit to close and sound the alarm, and means under the control of said locking device for rendering said alarm circuit operative and inoperative at will.
